(57) **CLAIM**

The ornamental design for a camera, as shown and described.

DESCRIPTION

FIG. 1 is a top, front and side perspective view of the camera showing my new design;

FIG. 2 is a front elevational view thereof;

FIG. 3 is a rear elevational view thereof;

FIG. 4 is a bottom plan view thereof;

FIG. 5 is a side elevational view thereof from the left of FIG. 2; and,

FIG. 6 is a side elevational view thereof from the right of FIG. 2.

The material in broken lines shows the environment in which the present invention is to be found, and is not claimed.
